CAN OPENING MACHINE

John S. Townsend and Leslie R. Tansley, Chicago, Ill., assignors to Wilson & Bennett Manufacturing Company, Chicago, Ill.

Application March 10, 1934, Serial No. 715,028

9 Claims. (Cl. 81—3.1)

There are various containers in use such as cans, pails and barrels having covers provided with fastening lugs and such lugs are usually provided with holes for convenience in using a tool such as a screw driver for opening the container. These covers are usually provided with a considerable number of such lugs, 16 being a common number for standard sized pails. The present machine is for the purpose of loosening or prying out all of such lugs simultaneously so that the cover can be quickly removed.

The objects of this invention are to provide a new machine for opening cans or containers which may be readily applied to the container and which will quickly pry out or release a plurality of fastening lugs in a single operation; to provide a pail opening machine having a plurality of lug bending or releasing members with means for simultaneously actuating the same; to provide a machine of this character having opening members with chisel points or the like adapted to engage with the holes in the cover lugs with means for directing the same into engagement with the holes and means for actuating the members to pry the lugs to open position; and to provide such other novel features and advantages as will appear from the following description.

In the accompanying drawings illustrating this invention,

Figure 1 is a vertical sectional view showing the machine applied to a can or pail;

Figure 2 is a sectional plan view taken on the line 2—2 of Figure 1;

Figure 3 is an enlarged detail illustrating the operation of the opening tools or prys; and

Figure 4 is a detail of one of the opening prys or fingers.

The pail or can 6 is shown with a cover 7 having lugs 8 with perforations 9 of the kind referred to. The opening machine has a base or support 10 which fits closely within the recess portion of the cover and has a plurality of outwardly extending projections 11 which rest on the top of the cover flange as shown in Figures 1 and 2. A post 12 extends upwardly from the center boss 13 of the base and is rigidly secured to the base. A sleeve 14 is slidably mounted on the post 12 and is limited in its movement by a lower collar 15 and an upper collar 16. A plurality of arms 17 are pivoted at 18 to the sleeve 14 and extend outwardly after the fashion of umbrella ribs. These arms generally correspond to the number of lugs on the pails to be opened. They extend out through slots 18' between guide-posts 19 which extend upwardly from the base 10 and

which may be formed integrally therewith. The upper ends of these posts are connected by a ring 20 which also serves in the nature of a stop or guide for the arms. The lower edges of the arms rest on the shoulder 21 at the outer periphery of the base and slide in and out thereover. An annular resilient member such as a coil garter spring 22 engages with all of the arms 17, each arm being provided with a clip 23 to hold the spring in operative position. The spring is under tension and tends to swing the arms downwardly against the shoulder or bearing 21.

Each arm 17 has a lug engaging tool 24 pivoted at 25 thereto. Each tool is in the nature of a pry or wedge-shaped finger which is bifurcated 15 at its outer end or provided with a slot 26 for receiving the end of the arm 17. A shoulder 27 engages with the lower edge of the arm and limits the swinging movement of the pry in one direction. Each pry is provided with a spring 28 20 which tends to hold it in raised or engaging position as shown in Figure 1. The inner end of each pry has a point or wedge-shaped portion 29 for engagement with the hole or slot 9 in the lug.

Two levers 30 are pivoted at 31 to the sleeve 25 14 and extend upwardly and outwardly, being provided at their outer ends with handles 32. Toggle links 33 are pivoted at their lower ends to brackets or bearings 34 on the base 10 and are pivotally connected at their upper ends with 30 the levers 30 by means of pivots 34^a which are spaced at a short distance from the inner ends of said levers.

When a container is to be opened the operator lifts the machine by the handles 32 and 35 spots it on the cover with the edges 29 of the opening prys or tools 24 opposed to the slots or holes 9 in the lugs. He then presses down on the handles, thereby raising the sleeve 14 and consequently the inner ends of the arms 17. 40 As these arms move upwardly the wedges or points 29 enter the holes 9 as shown in dotted lines in Figure 3. The further action then simulates very closely the action of a screw driver when used for this purpose. As the sleeve continues to move upwardly the outer ends of the prys 24 swing upwardly about their inner points as centers until the inner faces of the prys engage with the outer edge of the cover bead or flange above the lugs which tends to force the 50 lower ends of the prys outwardly thereby prying the lugs out until finally their lower ends swing out to the position approximately shown in Figure 3, and thereby fully freeing the lugs from the pail flange or bead. During the final bend- 55

ing movement it will be seen that as the handles 32 are swung downwardly there is a toggle action provided by the links 33 and the short pivoted ends of the handle levers which greatly 5 assist in making the final lug opening movement comparatively easy.

When the handle levers 30 are again raised the sleeve 14 and other parts move back to their initial or normal position and the springs 28 return 10 the pries to their lug engaging positions as first described.

While the machine has been described in connection with the opening of covers having perforated lugs it will be noted that it may be 15 adapted for other types of lugs or for removing other types of covers and therefore we do not wish to have the invention limited to the particular apparatus shown and described except as specified in the following claims in which we 20 claim:

1. A machine for opening containers having covers with inwardly bent fastening portions comprising a plurality of opening members adapted to engage with said fastening portions 25 handles for operating the machine and means operated by downward movement of the handles for actuating said members to cause them to engage with said fastening portions of the cover and to bend the same to releasing position.

2. An apparatus for releasing a cover having a plurality of fastening portions from a container, comprising a plurality of opening members adapted to engage with said fastening portions 30 of the cover to bend the same to open position, means for supporting said members, operating levers having handles for actuating said apparatus and means actuated by downward movement of the handles of said operating levers for simultaneously actuating all of said members to cause them to engage with and release the fastening portions of the cover.

3. In a machine for bending container cover lugs to opening position, the combination of a base adapted to be positioned on the cover, a post extending upwardly from the base, a sleeve slidably mounted on the post, a plurality of arms pivoted to the sleeve and extending radially therefrom, pries pivoted to the arms, springs tending to hold the pries in position to engage 40 with the lugs, and means including downwardly pressed handle members for moving the sleeve upwardly to cause the pries to engage with the lugs and bend them to open position.

4. In a machine for opening cans or pails having covers provided with lugs having holes therethrough, the combination of a support to be positioned on the pail cover, a center post extending upwardly from the support, a sleeve mounted on the post, a plurality of arms extending outwardly from the sleeve, pries pivoted to the ends of the arms, springs engaging with the arms and the pries and tending to hold the free 50 ends of the pries in raised or engaging position for entering said holes, an annular spring engaging with the arms and tending to swing their lower ends inwardly, guides on the support for said arms, handle levers pivoted to the sleeve, and links pivotally connecting the handle levers and the support, said links serving as fulcrums for the handle levers when the same are moved 55 downwardly to raise the sleeve, the arrangement being such that said pries will engage with the holes in the lugs and bend the lugs outwardly for the purposes described.

5. In a container opening machine, the com-

bination of a base, a center post projecting upwardly from the base, a slide mounted on the post, arms extending outwardly from the slide, opening jaws pivoted to the outer ends of the arms and adapted to engage with lugs on the 5 container cover for bending the same, bearings on the base, handle levers pivoted to the slide, and links connecting the handle levers and said bearings, the arrangement being such that when the handle levers are swung downwardly the 10 slide will be raised and the arms will cause the opening jaws to engage with the lugs and bend the same outwardly.

6. A can opening machine comprising a base for engagement with the can cover, a post extending upwardly from the base, a slide mounted on said post, a plurality of arms extending outwardly from said member and slidably engaging with the outer periphery of the base, resilient means tending to swing the lower 20 ends of said arms inwardly, opening fingers pivoted to the outer ends of said arms and having chisel points for engagement with holes in the cover lugs, springs engaging with the arms and fingers and tending to hold the free ends 25 of the fingers in raised position, handle levers pivoted to said slide member, and links connecting the handle levers and base, the arrangement being such that when the handles are swung downwardly the slide member will be 30 raised and the arms will cause the opening fingers to engage with the cover lugs to pry them to open position.

7. In a machine for opening cans having covers provided with closing lugs having holes therethrough, the combination of a base adapted to fit within the cover, outwardly extending projections on the base for engagement with the cover flange, a plurality of pairs of posts extending upwardly from the outer periphery of the base 40 and providing vertical guideways, a ring connecting the upper ends of the posts, a center post extending upwardly from the base, a slide on said post, manually operated means for reciprocating said slide, a plurality of arms pivotally connected with the post and extending outwardly through said guideways and adapted to bear on the outer periphery of the base, means tending to swing the arms downwardly, fingers having bifurcated outer ends pivotally connected 45 with the outer ends of the arms, springs engaging with the arms and the fingers tending to swing the inner ends of the fingers upwardly against the arms, said fingers being straight on one side and beveled on the opposite side to provide wedge-like ends, the arrangement being such that when the slide is raised the fingers will 50 swing on their pivots until they engage with the bead of the cover, thereby causing the engaging ends to swing outwardly and bend the lugs to releasing position.

8. In a pail opening machine, the combination of a support for engagement with the pail cover, a post extending upwardly from the support, a sleeve slidably mounted on the post, handle levers pivotally connected with the sleeve, links connecting the handle levers with the base and providing fulcrums for said levers, radially arranged arms pivotally connected with the sleeve 70 and adapted to slide on the outer edge of the support, vertical guideways on the support for said arms, a garter spring engaging with all of said arms and tending to swing the same inwardly, pries pivotally mounted at the outer ends 75

of said arms and having sharpened inner ends for engagement with the cover lugs, springs tending to hold the pries in initial engaging position, said pries being adapted to engage with the cover bead to swing the lower ends of the pries outwardly after they have been brought into engagement with the cover lugs.

5. In a machine for opening pails having covers provided with closing lugs which are bent under a flange on the pail for holding the cover in position, the combination of a base which engages with and is supported by the pail cover during the opening operation, a series of circumferentially arranged opening fingers which

engage with the lugs to bend them to free the cover from the pail, movable supports mounted on the base for supporting said fingers in normal position to engage with said lugs, manually operable means coacting with the base and said supports for moving the supports, and means for pivotally mounting said fingers on said supports whereby the ends of the fingers will move inwardly to engage with the lugs and then swing outwardly to pry the lugs to opening position 10 when the supports are actuated by said manually operable means.
